FIG. 7.

UNITED STATES PATENT OFFICE.

HENRY S. MARSH AND RALF S. COCHRAN, OF YOUNGSTOWN, OHIO.

METHOD OF AND APPARATUS FOR RECOVERING SPENT PICKLING SOLUTIONS.

Application filed December 24, 1920. Serial No. 432,852.

To all whom it may concern:

Be it known that we, HENRY S. MARSH and RALF S. COCHRAN, residing at Youngstown, in the county of Mahoning and State 5 of Ohio, both citizens of the United States, have invented or discovered certain new and useful Improvements in Method of and Apparatus for Recovering Spent Pickling Solutions, of which improvements the following 10 is a specification.

Our invention relates to the recovery of spent pickling solutions, solutions initially acid and which through continued use have become heavily laden with salts in solution. 15 Such are the exhausted and enfeebled solutions which come from the pickling vats of steel mills. Our present invention consists in improvements upon the method and apparatus set forth and described in our application for United States Letters Patent, 20 Serial No. 350,383, filed January 9, 1920, and allowed October 18, 1920. The invention, primarily intended for the purpose stated, is of wider applicability, as eventually 25 will appear.

Our invention is illustrated in the accompanying drawings. Fig. I is a plan view from above of reclaiming apparatus in the construction and operation of which our 30 present improvements in apparatus and in method are realized; Fig. II is a view in vertical longitudinal section, on the plane indicated by the line II-II, Fig. I; Fig. III is a view in transverse vertical section, 35 the plane of section being that indicated by the line III-III, Fig. I; Figs. IV and V are views to larger scale and in side and front elevation of a formation which we prefer for certain loops or coils employed 40 to effect heat exchange, as will be explained below; Fig. VI is a view in elevation, and diagrammatic in character, particularly illustrating the handling of the salt when removed from the precipitation chamber; 45 Fig. VII is a diagrammatic view in plan of the layout of the whole.

Referring to Fig. I, we provide two troughs 1 and 2 of heat-insulating material 50 resistant to acid attack. Conveniently these troughs are made of wood. They are arranged in series, to receive and convey an advancing stream of pickling solution; a supply pipe 3 enters trough 1 at one end; a connecting pipe 4 leads from trough 1, at 55 the end remote from the entry of pipe 3 (the

down-stream end), to one end of trough 2; from the farther end of trough 2 a delivery pipe 5 leads. The intake through pipe 3 may come directly from the pickling vat, or it may come from a storage tank. Fig. 60 VII shows a storage tank 6 of particular structure. The spent acid from the pickling tanks, elevated if need be by suitable means, such as an air lift, flows through a supply pipe 7 and enters tank 6 through a screen 8. 65 The space within the tank, between inlet and outlet is divided by a series of baffle partitions 9, so arranged as to cause the solution to advance through the tank in a succession of vertical, alternately rising and 70 descending reaches. An arrangement of partitions such as to effect this end will presently be explained in describing trough 1, and further description on this point 75 will be deferred. The contents of the tank (initially hot) may or may not be heated additionally. Heating means are well known, and in our earlier application already alluded to we have indicated such means. 80

The reason for so screening the flow of pickling solution and then driving it in circuitous course is to separate dirt—to separate by deposit such heavy substance as scale and to remove by skimming such light substance as sawdust. The purpose is that, if the recovered salt is to be used commercially, such substances as might otherwise accumulate with the salt and adulterate it, will be removed before the solution leaves tank 85 6. If the recovered salt is to be wasted, or if it is to be used in such manner that contamination is unimportant, such special means for cleaning need not be employed. 90

Returning now to particular description 95 of trough 1, its internal construction will be understood on comparing Figs. I and III. It is a long, deep trough; the space within is divided by transverse partitions so proportioned and arranged as to cause the advancing stream to flow up and down through a succession of vertically arranged passageways. The partitions stand alternately at different heights; the succession of partitions 10 stand free of the bottom of the tank and somewhat above the level of the flowing stream. The alternate partitions 11 rise from the bottom of the tank and do not reach the surface of the flowing stream. This arrangement of partitions will 100 105 110

be clearly understood from a glance at Fig. II, which is as has been said, a section through trough 2 and in which the partitions 20 and 21 are arranged substantially as partitions 10 and 11 are arranged in trough 1. The level of the upper edges of partitions 11 in trough 1 and 21 in trough 2 is, in Figure III, indicated by the line *a*—*b*; the level of the partitions 10 and 20 is indicated by the line *c*—*d*; the level of the lower edges of partitions 10 and 20 is indicated by the line *e*—*f*. Of the level of the lower edges of partitions 21, more remains to be said, when we come to describe trough 2.

It may now properly be remarked that the partitions 9 in tank 6 are arranged in substantially the same manner, to effect the same vertical circuitous flow.

20 The progress of the flow of the solution through trough 1 will be down from intake 3, beneath the first partition 10, up and over the first partition 11, then down again; circuitous flow continues until at length the 25 stream, rising beyond the last partition 10 escapes through the pipe 4.

Into the passageways formed for the flowing stream by and between these partitions 10 and 11—into some or all of them, as may 30 be found expedient, depend coils 12, such as are particularly illustrated in Figs. IV and V, of a circulation pipe, presently to be more particularly described and characterized. Suffice it here to say that these coils 35 are formed of heat-conducting material, (conveniently of copper) and the structure in this detail is essentially a heat-exchanger. Manifestly, the particular form of coil illustrated in Figs. IV and V is exemplary. 40 Such particular arrangement within the knowledge of the engineer, will be resorted to as he may prefer, to provide the essential extended heat-exchanging walls.

In the bottom of trough 1 and extending 45 longitudinally throughout its extent, or throughout so much of its extent at least as is occupied by the heat-exchanging apparatus indicated, lie pipes 14, perforated at intervals and carrying under pressure a suitable 50 gas—conveniently air—to bubble through the stream as it flows. The function of such inblown gas is to agitate the flowing stream of solution, and to intensify and quicken the heat-exchanging action.

55 Coming now to trough 2, it is in general features like trough 1. Fig. III shows it to be deeper than trough 1, and to be hopper shaped at the bottom. Partitions 21 are at their lower ends so shaped and positioned 60 as to afford a continuous space in the bottom of the trough, in which space the precipitated salt collects, and from which the collected salt may by suitable means be withdrawn; for example, by the spiral conveyor 28.

It is desirable to agitate the stream in trough 2, as well as in trough 1, and that by like means. The accumulating of precipitate in trough 2 and the removal of the accumulation render it undesirable to arrange pipes for injection of gas along the bottom of trough 2; instead, pipes 24 extend above tank 2, and these are provided with depending branches, and these extend down to approximately the 75 bottom of trough 2 and there they discharge their jets of inblown gas.

In the passageways of trough 2, as in those of trough 1, coils of pipe are arranged, to serve as heat-exchanging members. The 80 solution as it flows from trough 2 through conduit 5 returns upon itself, and traverses in turn certain of the coils arranged in the passageways of trough 2 (those designated 85 22) and then the coils 12 in the passageways of trough 1. The direction of flow of this return branch of the looped stream is countercurrent to the branch advancing through the passageways and inundating the coils. Fig. I diagrammatically shows 90 three coils in each passageway. The number may be varied. From the coils 12 in tank 1 the now reclaimed solution flows through pipe 34 to storage tank 30, or, it 95 may be, directly to the pickling vats.

We have just remarked that the return branch of the looped stream traverses "certain" of the coils arranged in the passageways of trough 2. The drawings (Fig. I) show the trough subdivided by the partitions 20, 21, into twelve passageways; in all of these passageways, excepting the last two ("last" relatively to the right-to-left flow of the advancing stream) coils are shown to be placed. Through the coils of 100 the first five passageways the return branch of the stream advances, from left to right, 105 countercurrent to the incoming stream.

It now appears that the stream as it flows through the apparatus flows in loop form, 110 the branches of the loop in heat-transferring relation, one to the other. The "loop," a phrase which we shall hereafter employ, designates the course of the stream, from its advance beyond passageway A, Fig. I, to its return to the point B where it is about to enter the first of the coils 22.

In our earlier application mentioned above we describe apparatus in which the flowing stream is looped to effect the same 120 ends as those here contemplated. The flow of the liquid under treatment is there maintained by gravity. With refinement and elaboration of apparatus we find it desirable to pump the liquid through the return branch of the circuit; and to that end we 125 show in Fig. I a pump 31, arranged in conduit 5 between the point of emergence from trough 2 and the point where the stream enters the first of the coils 22.

We have said that the first five of the twelve passageways of trough 2 contain coils 22. It will be observed that of the remaining seven passageways, the first five 5 contain similar coils, 25; and it will be observed further that nozzles for blowing in agitating gas enter all of the passageways of trough 2, excepting the last. This last passageway is free both of heat-exchanging 10 coils and of gas nozzles; the next passageway to the last, though it contains gas nozzles, is free of heat-exchanging coils.

The coils 25 in the five intermediate passageways of trough 2 are part of a refrigeration unit; through them courses a suitable cooling fluid—it may be brine, it may be ammonia, it may be other fluid, depending on the particular nature of the refrigeration unit chosen. Many sorts of refrigeration apparatus are known, and the engineer may exercise his judgment or preference in selecting one or the other. The flow of cooling fluid through the bank of coils 25 is preferably from left to right, Fig. I—25 countercurrent to the right-to-left advance of the incoming stream through trough 2.

The number of passageways into which the troughs are subdivided is not important—indeed, the provision of a plurality 30 of troughs is, in the broader aspect of the problem, a matter of convenience in assembly and arrangement of component pieces of apparatus. But (with the arrangement of trough 2 as shown in Fig. I particularly 35 in view), the essential features are that the advancing incoming stream shall wash, first, the heat-exchanging coils 22 in which the return stream flows, that it shall then wash, second, the coils 25 in which the cooling 40 agent flows, and that it shall then flow through a further portion of trough 2 free of heat-exchanging coils. It is further desirable that agitation of the advancing stream maintained where the stream washes 45 coils 22 and 25, shall continue in that portion of the trough 2 which is free of coils, but shall not continue to the end of trough 2.

It will in some cases be found that because of depletion in volume the return 50 stream will not be adequate to afford the preliminary cooling desired. In such case supplemental cooling means may be resorted to. For example certain of the coils 12 in trough 1 may be taken out of the line 55 of circulation of the returning stream of reclaimed solution, and through them cold water (or other cooling fluid) may be circulated.

Again, because of diminution of volume 60 of liquid, consequent upon crystallization of the salt (ordinarily copperas, carrying 45% water of crystallization), the reclaimed solution may be of too great strength, as regards its acid content. In such case an additional supply of water may be introduced.

The feed pipe 15, through which liquid recovered in centrifuge 28 may be returned, is a suitable pipe for the introduction of additional supplies of water also. If the water so introduced be cold, it may in virtue of that characteristic correct the difficulty (if such difficulty exists) just mentioned, of too little cooling effect of the outgoing liquid upon the incoming.

Note has been made above of the fact that 75 the precipitated salt is removed from the bottom of trough 2 by means of a spiral conveyor 23. This conveyor, be it noted, is arranged to remove the salt in a left-to-right direction, moving it from the cooler 80 to the warmer end of the trough. Such is the preferred, though not the necessary, arrangement. At the right-hand end of trough 2 conveyor 23 delivers the salt to a sump 26, whence it is raised by a second 85 spiral conveyor, arranged in an inclined spout 27, to a level higher than the surface of liquid in troughs 1 and 2. From spout 27 the slush of crystals and acid passes in continuous feed to a tank 40, and thence in 90 successive charges to a centrifuge 28. From the centrifuge the liquid returns, impelled if need be by an air lift or equivalent apparatus, and reenters the stream flowing in the reclaiming apparatus. This reentry 95 may be at any desired point. For example, it may enter the trough 2, through pipe 33.

In a small installation it may be desirable to unite the two tanks end to end, making a single tank (as obviously may be 100 done). In such case, the removal of crystals would preferably be from an intermediate point in the length of the trough, and the particular kind of conveyor would be that which the engineer prefers.

The salt relieved of the greater part of the accompanying liquid, but still damp, descends from the centrifuge to a vibratory, slightly inclined, somewhat roughened, and preferably somewhat heated conveyor platform 29. The means of heating may be such as the engineer prefers. Advantageously also the salt spread upon conveyor 29 may be blown upon by a suitably placed fan. By such means the salt is thoroughly 110 dried, and from the conveyor the dried salt passes to suitable storage bin or receptacle for shipment. Instead of such a platform conveyor as the drawings show and as the foregoing sentences characterize, we may 115 employ a steam-jacketed drying and mixing conveyor, of the sort now on the market and known to engineers.

Recurring to the course of the liquid flowing from trough 2, an overflow pipe 32 is 125 provided, leading directly from trough 2 to tank 30. In case of trouble with the pump, the liquid will thus be cared for.

The operation of the apparatus now described, in which operation our improved 130

method is practiced, may be briefly indicated. The solution to be treated, flowing through conduit 3, enters tank 1; following the circuitous vertical course described, it 5 passes through tank 1, and, flowing thence through conduit 4, it enters tank 2 and traverses it in like course. Emerging from tank 2, it flows through conduit 5, back through coils 22 in trough 2, and then 10 through coils 12 in trough 1, and on to a suitable place of storage or consumption. Within trough 2 and beyond the bank of coils 22, the advancing stream encounters first the bank of coils 25. It then enters a 15 passageway where the blowing with air which has attended its advance thus far through the troughs is continued, but where no further cooling is exercised upon it, and then before it passes from trough 2 it traverses a passageway in which it is neither cooled nor agitated.

The liquid under treatment enters trough 1 at high temperature, not far below the boiling point. The refrigerating apparatus 25 (coils 25) is such as to reduce the temperature of the liquid under treatment to or slightly below the freezing point of water (0° C.). But on the way from inlet to refrigerator the advancing stream comes into 30 heat-exchanging relation with the return stream passing from the refrigerator. The liquid of this stream is reclaimed solution, and it at the beginning of the return flow is cold (the temperature is near freezing). 35 Volumetrically the return stream is less than the entering stream, because of the removal of the salt (carrying from the liquid, be it remembered, relatively large quantities of water of crystallization). By virtue of the 40 heat exchange, the entering solution on reaching the refrigerator has already been cooled to a relatively low degree (10° C., or thereabouts), and, accordingly, less refrigeration is required; while the reclaimed 45 solution passes from the apparatus heated to a degree approximating that required in the pickling vat, to which it may directly pass.

Proportions are such that the entering 50 solution is in trough 1 cooled to a point near but not beyond that of salt precipitation (21°—43° C.). In trough 2 temperature is reduced to a point somewhat below the freezing point of water, and substantially to 55 the freezing point of the solution—which is a few degrees below 0° C. Agitation of the stream as it flows expedites heat transfer and keeps the heat-transfer surface clean of salt-crystals, and, furthermore, agitation is 60 effective to prevent formation upon the surfaces of coils 25 of ice crystals; for, if the liquid be relatively undisturbed, the water will, when a temperature below zero is reached, tend so to separate and crystallize. 65 Precipitation begins soon after the incom-

ing solution enters trough 2 and progresses as temperature falls. The inblown air has this further effect, in addition to those noted above, that the precipitate is not massive, but is an accumulation of finely divided 70 crystals.

We have been particular to describe provision such that the liquid under treatment, after complete refrigeration passes on through a passageway where still it is agitated by inblown gas, and then ultimately enters a passageway where it is no longer so agitated. Agitation prolonged beyond cooling is effective to complete precipitation; ultimate freedom from agitation allows the precipitate to settle, and permits the drawing off through conduit 5 of clear reclaimed liquid.

We have been careful to explain that the precipitate is preferably carried toward and ultimately delivered from the warmer end of trough 2. Of course in carrying crystals from cooler to warmer portions of the body of liquid, some portion will be redissolved. But the quantity so redissolved will be inconsiderable, and there will be a more than countervailing gain, in the cooling effect that the body of precipitate will exert on the portions of the liquid toward the warmer end of the trough.

We have now described the invention in its application to the specific problem of reclaiming spent pickling solution. As we intimated at the beginning and as now is manifest, the invention is applicable to solutions generally, and will be found advantageous, wherever the desirability appears of obtaining precipitation with a minimum loss of heat.

We claim:

1. The method herein described of reclaiming spent pickling solution, which consists in causing the solution to flow in a looped circuit, the return branch of the circuit confined within heat-conducting walls 110 being submerged in the outgoing branch, and cooling the stream in the loop of the circuit.

2. The method herein described of reclaiming spent pickling solution, which consists in causing the solution to flow in a looped circuit, the branches of the circuit in heat-transferring relation one to the other, causing the stream to submerge a heat-absorbing body arranged in the loop of the circuit, and agitating the stream of solution where it sweeps across the heat-absorbing body.

3. The method herein described of reclaiming spent pickling solution, which consists in causing the solution to flow in a looped circuit, the branches of the circuit in heat-transferring relation one to the other, causing the stream to submerge a heat-absorbing body arranged in the loop 130

of the circuit, and causing bubbles of gas to rise through the stream of solution in the region where it sweeps across the heat-absorbing body.

5 4. The method herein described of reclaiming spent pickling solution, which consists in causing the solution to flow countercurrent in loop form, the branches of the circuit in heat-exchanging relation one to the other, cooling the flowing stream throughout a portion of the loop, and collecting precipitate from the flowing stream throughout the region of cooling and beyond.

10 15. 5. The method herein described of reclaiming spent pickling solution, which consists in causing the solution to flow countercurrent in loop form, the branches of the circuit in heat-exchanging relation one to the other, cooling the flowing stream in the loop, gathering precipitate from the loop, separating from the precipitate gathered its accompanying liquid, and reintroducing to the circuit the liquid so separated.

20 25. 6. The method herein described of reclaiming spent pickling solution, which consists in causing the solution to flow countercurrent in loop form, the branches of the circuit in heat-exchanging relation one to the other, cooling the flowing stream in the loop, gathering precipitate from the loop, separating from the precipitate gathered its accompanying liquid, and reintroducing to the stream in the incoming branch of the circuit the liquid so separated.

30 35. 7. The method herein described of reclaiming spent pickling solution, which consists in causing a stream of solution to flow countercurrent in loop form, the branches of the circuit in heat-transferring relation one to the other, cooling the flowing stream and precipitating the salt in the loop, and introducing an added stream of solvent into the incoming branch of the circuit.

40 45. 8. In the operation of reclaiming spent pickling solution, the step herein described of effecting heat exchange which consists in causing a colder stream to flow in a conduit of heat-conducting material arranged within a vertically flowing warmer stream, and in causing a gas to bubble through the stream last named from a point beneath such conduit.

50 55. 9. The method herein described of reclaiming spent pickling solution which consists in causing the solution to flow in devious course through a succession of vertically disposed rising and descending reaches, cooling the solution after it has traversed said reaches and precipitating thereby its burden of salt, and then causing the unburdened stream to return through a conduit of heat-conducting material extending within said reaches.

60 65. 10. The method herein described of re-

claiming spent pickling solution which consists in bringing the solution into contact with a heat-absorbing body and, as the temperature falls below the freezing point of the solvent, causing bubbles of gas to ascend through the liquid and across the surface of the heat-absorbing body.

70 11. The method herein described of reclaiming spent pickling solution which consists in causing a stream of the solution to sweep across the surface of a heat-absorbing body and, as the temperature falls below the freezing point of the solvent, agitating the stream.

75 80 12. The method herein described of reclaiming spent pickling solution which consists in effecting precipitation by causing the solution under treatment to flow in a stream over a cooling surface, and withdrawing the precipitate through the stream 85 in a direction opposite to its flow.

85 90 13. In apparatus for reclaiming spent pickling solution, means for causing the solution to flow in a loop-formed stream with the branches of the circuit in heat-transferring relation one to the other, said means including a precipitation chamber in the loop, and cooling means effective upon the flowing stream up to a point short of the end of the precipitation chamber, substantially as described.

95 100 14. In apparatus for reclaiming spent pickling solution, means for causing the solution to flow in a loop-formed stream, with the branches of the circuit in heat-transferring relation one to the other, a heat-absorbing body arranged to be submerged in the flowing stream of solution in the loop thereof, and means for agitating the stream of solution where it sweeps across such heat-absorbing body, substantially as described.

105 110 15. In apparatus for reclaiming spent pickling solution, means for causing the solution to flow in a loop-formed stream, with the branches of the circuit in heat-transferring relation one to the other, a heat-absorbing body arranged to be submerged by the flowing stream in the loop thereof, and means for injecting gas into the flowing stream at a point beneath such cooling body, substantially as described.

115 120 16. In apparatus for reclaiming spent pickling solution, means for causing the solution to flow in a loop-formed stream, the return branch of the stream traversing a heat-conducting-walled conduit submerged in a vertically flowing reach of said stream, and means for injecting gas into the stream at a point beneath said conduit, substantially as described.

125 130 17. In apparatus for reclaiming spent pickling solution, a heat exchanging unit consisting of a vertically disposed passageway for liquid, a conduit disposed in said passageway, and means for injecting an agi-

tating gas into the stream flowing in said passageway at a point beneath said conduit, substantially as described.

18. In apparatus for reclaiming spent pickling solution, means for causing the solution to flow in loop form, the branches of the circuit in heat-exchanging relation one to the other, a conduit with heat-conducting walls arranged to be submerged in the flowing stream of pickling solution, in the loop thereof, means for causing a cooling fluid to flow in said conduit, and means for injecting gas into the stream of pickling solution at a point beneath said conduit, substantially as described.

19. In apparatus for reclaiming spent pickling solution, means for causing a stream of solution to flow countercurrent in circuit form, the branches of the circuit in heat-exchanging relation one to the other, means for cooling a portion of the loop, and a device arranged at a point in the line of flow beyond the region of cooling for removing precipitate from the apparatus.

20. In apparatus for the reclaiming of spent pickling solution the combination of a conductor for a stream of solution under treatment, means for effecting precipitation of salt from the stream, such means consisting of a cooling element arranged within the conductor and adapted to be submerged in the flowing stream, and means for withdrawing from the conductor, and in a direction from the cooler to the warmer end thereof, the precipitated salt, substantially as described.

21. In apparatus for recovering spent pickling solution, means for causing the solution to flow in a looped stream, the branches of the circuit in heat-communicating relation one to the other, means for cooling the stream as it flows through the loop, means for gathering precipitate from the stream in the loop, means for separating from the precipitate so gathered its accompanying liquid, and means for returning to the flowing stream the liquid so separated, substantially as described.

22. In apparatus for the recovery of spent pickling solution the combination of a passageway, means for precipitating salt in finely divided form from a solution flowing in said passageway, means for removing the precipitated salt from said passageway, and means for separating from the precipitate so removed and for returning to the passageway mother liquor removed with said precipitate, substantially as described.

23. In apparatus for reclaiming spent pickling solution, means for causing the solution to flow in devious course through a succession of vertically disposed rising and descending reaches, a return conduit for the solution formed of heat-conducting material and arranged to be submerged in the flowing

stream in one of the reaches mentioned above, means for cooling the stream as it flows in the circuit so formed, and means for removing from the apparatus precipitate collected by gravity at the bottom of said reaches.

24. In apparatus for reclaiming spent pickling solution, means for causing the solution to flow in devious course through a succession of three vertically disposed rising and descending reaches, a return conduit for the solution formed of heat conducting material and arranged to be swept across by the stream in the first of the reaches mentioned, and means for cooling the flowing stream in the second of such reaches, substantially as described.

25. In apparatus for reclaiming spent pickling solution, means for causing the solution to flow in devious course through a succession of vertically disposed rising and descending reaches, means for agitating the stream as it flows in such reaches, excepting the last, means for cooling the flowing stream arranged in one of the reaches in which agitation is maintained other than the last, and a return conduit for the flowing stream formed of heat-conducting material and arranged to be swept across by the flowing stream in one of such reaches anterior to that in which said cooling means are arranged, substantially as described.

26. In apparatus for reclaiming spent pickling solution, four vertically disposed passageways opening below to a common receiving space for precipitate, and arranged to carry a stream of the solution in alternately ascending and descending reaches, a conduit formed of heat-conducting material arranged to be submerged in the stream flowing through the first passageway, separate means for cooling the stream as it flows through the second passageway, means for causing an agitating gas to rise through the stream as it flows in the first second and third passageways, and means for removing the precipitate from such receiving space, substantially as described.

27. In apparatus for reclaiming spent pickling solution, a trough, transverse partitions in said trough dividing the space within and directing the flow of a stream of pickling solution introduced at one end in a succession of vertically alternately rising and descending reaches, means for cooling the advancing stream, and means for effecting a heat exchange between the cooled stream flowing from the trough and the thitherto uncooled stream advancing in the trough, substantially as described.

28. In apparatus for reclaiming spent pickling solution, a trough, transverse partitions arranged in said trough, and directing the flow of a stream of solution flowing through the trough into a succession of alter-

nately rising and descending reaches, a return conduit for the solution passing from the trough with heat-exchanging portions arranged to be swept by the stream in the 5 earlier reaches within the trough, and cooling means operative upon the stream in intermediate reaches of the trough, substantially as described.

29. In apparatus for reclaiming spent 10 pickling solution a plurality of troughs subdivided within into a succession of alternately ascending and descending passageways arranged in series and forming a continuous line of flow for the solution to be 15 reclaimed, a conduit leading from the discharge end of the second trough in the line of flow and provided with coils of heat-conducting material depending into the passageways of the first trough, and cooling means 20 effective upon the flowing stream as it advances through the second trough, substantially as described.

30. In apparatus for recovering spent 25 pickling solution two tanks arranged in series and adapted to carry a flowing stream of solution, subdivided internally into successions of passageways through which the advancing stream flows alternately upward and downward, a conductor leading from 30 the discharge end of the second trough in the line of flow, and provided with coils formed of heat-conducting material depending some of them into passageways of the second trough adjacent the inlet end there- 35 of, and other of said coils depending into passageways in the first trough, a coil of heat-conducting material depending into a passageway of the second trough adjacent the discharge end thereof, and means for caus- 40 ing a cooling fluid to flow through the coil last named, substantially as described.

31. In apparatus for recovering spent 45 pickling solution the combination of means for causing a stream of solution under treatment to advance in a succession of vertically

ascending and descending reaches, means for cooling the advancing stream below the point of precipitation, such means including a conduit of heat conducting material immersed in the flowing stream and conveying 50 the looped-back solution after it has traversed the reaches first defined, a refrigerator element in the loop so formed, and an auxiliary cooling agent operative upon the stream as it approaches the loop and means 55 for removing from the apparatus precipitated salt, substantially as described.

32. In apparatus for recovering spent 60 pickling solution, the combination of means for precipitating, removing, and draining the salt, and a material-agitating conveyor maintained at elevated temperature leading to the point of delivery, substantially as described.

33. In apparatus for recovering spent 65 pickling solution, the combination of means for precipitating, removing, and draining the salt, a material-agitating conveyor maintained at elevated temperature, leading to the point of delivery, and means for maintaining a circulation of air over the salt when borne by said conveyor, substantially as described.

34. The method herein described of precipitating a salt from a solution which consists in causing the solution to flow counter-current in loop form, the branches of the circuit in heat-exchanging relation one to another, cooling the flowing stream throughout a portion of the loop, and collecting 70 precipitate from the flowing stream throughout the region of cooling and beyond.

In testimony whereof we have hereunto set our hands.

HENRY S. MARSH.
RALF S. COCHRAN.
